UNITED STATES PATENT OFFICE.

FRANCIS P. GALVIN, OF BUFFALO, NEW YORK, ASSIGNOR OF ONE-HALF TO WILLIAM L. FOX, OF BUFFALO, NEW YORK.

RADIATOR.

989,243.

Specification of Letters Patent. Patented Apr. 11, 1911.

Application filed November 27, 1908. Serial No. 464,769.

To all whom it may concern:

Be it known that I, FRANCIS P. GALVIN, a citizen of the United States, residing at Buffalo, in the county of Erie and State of New York, have invented a new and useful Improvement in Radiators, of which the following is a specification.

This invention relates to radiators for use in heating systems, and more particularly to steam radiators of that kind which are composed of a plurality of radiating sections having controlling means for the heating fluid which permit any one or more of said sections to be used independently of the other section, or sections, for regulating the heat of the radiator as desired.

The objects of the invention are to produce a practical and desirable sectional radiator of this sort which is of simple construction, such that it can be economically manufactured and installed; also to make a radiator of a plurality of independently controlled sections which are constructed and arranged longitudinally side by side in such manner that the radiator, as a whole, will resemble the ordinary radiator built up of a series of transverse communicating loops or sections and will have a large radiating surface; also to improve sectional radiators of this type in the respects hereinafter described and set forth in the claims.

In the accompanying drawings: Figure 1 is a side elevation of a radiator partly in section embodying the invention. Fig. 2 is an elevation of one end thereof. Fig. 3 is an elevation of the other end thereof, showing the air valve and connections. Fig. 4 is a transverse sectional elevation thereof on line 4—4, Fig. 1. Fig. 5 is an end view of the sections separated.

Like letters of reference refer to like parts in the several figures.

The radiator illustrated in the drawings is provided with connections for use in a single pipe steam heating system. The improvements are not, however, restricted in application to radiators for single pipe steam systems, and the sectional construction herein-after described is applicable to radiators for use in other kinds of steam and hot water heating systems.

The radiator is preferably composed of three longitudinal sections; two outer sections A A, and an intermediate or middle section B arranged between the outer sec-

tions. Each section consists of a hollow body or casting which is preferably in one piece, or continuous, from end to end of the radiator, and each outer section is formed with upright radiating loops, columns or portions a which are separated by intervening air circulating spaces and communicate at their upper and lower ends through hollow connecting portions a' . In the case of long radiators it is desirable, from a manufacturing standpoint, to join a plurality of the short sections described to form each long section of the radiator instead of making each section in one piece from end to end of the radiator. The intermediate section is also preferably, though not necessarily, formed like the outer sections, with spaced upright radiating loops, columns or portions communicating at their tops and bottoms. The outer sections A A are provided with supporting feet or portions but the intermediate section is secured to and supported entirely by the outer sections above the floor and has no feet. Preferably the outer sections are taller than the intermediate section B and have top and bottom extensions a^2 which approach each other above and below the intermediate section so as to practically inclose the intermediate section except at its ends. By making the intermediate section with small external lugs b , Fig. 5, adapted to bear against the inner sides of the outer sections, the adjoining faces of the sections can be held out of contact with each other when the sections are assembled, thus forming additional narrow air circulating spaces b' between the outer and intermediate sections. The provision of the lugs also enables sections to be more readily fitted together, as the lugs can be quickly cut down as may be required to allow for irregularities in the sections which would otherwise interfere with the proper assembling of the sections. When the three sections thus formed are assembled, the radiator as a whole is very similar in shape and general appearance to the ordinary radiator made up of transverse loops or sections, and it has a radiating surface of substantially the same area as the ordinary radiator of like size. The intermediate section is thus confined and supported in place by the outer sections.

While three sections constructed and arranged as described are preferred, the radiator could consist of only two or more

than three sections, but whatever number of sections is employed the outer sections are preferably constructed substantially as described so as to give the radiator substantially the same external appearance as the ordinary radiator with transverse loops.

C represents a steam supply pipe which is located at one end of the radiator and connects by branches c c' c² with the upper portions of the several sections A A B, and by branches d d' d² with the lower portions of the sections. The steam pipe is provided with the usual cut-off valve e and each of the upper branch pipes c c' c² is provided 10 with a separate valve E whereby the steam can be admitted to any one or more of the sections independently of the other section, or sections. A check valve F is provided in each of the lower branch pipes d d' d².

20 G represents an ordinary automatic air valve located at the opposite end of the radiator and connected with the several sections by branch pipes g controlled by hand valves g'. A separate air valve for each section 25 could be used, if preferred, instead of the single valve having the separate connections to the several sections.

When any section is to be heated the valve E therefor is opened to allow steam to enter 30 the section. The check valves F for the other sections prevent the steam from entering them at the bottom so long as the supply valves E for such sections are closed, but the check valves permit the condensation to 35 flow from the sections back into the steam pipe. Thus any one or more of the sections may be heated so that the radiation is under control and capable of regulation.

The described steam connections are such 40 as would be used in a single pipe heating system, but it should be understood that the radiator would be differently piped for use in other heating systems, and the described sectional construction can be used with appropriate connections in different kinds of 45 steam heating systems and also in hot water heating systems.

The sections of the radiator are independent of each other and disconnected except by 50 the connections for the heating fluid and air at the ends of the radiator, and either section can be used alone, or the outer sections used without the intermediate section or sections, as a complete radiator.

55 I claim as my invention:

1. A radiator comprising outer and intermediate sections which are arranged side by side lengthwise of the radiator and are secured together in one structure, the outer

sections extending from end to end of said 60 intermediate section and projecting toward each other above said intermediate section and having upright radiating portions which communicate with each other but are separated by intervening air spaces, substantially 65 as set forth.

2. A radiator comprising outer and intermediate sections arranged side by side lengthwise of the radiator and secured together in one structure, the outer sections extending 70 from end to end of the radiator and having upright radiating portions which communicate with each other but are separated by intervening air spaces, and said outer sections having bottom extensions which project 75 toward each other, substantially as set forth.

3. A radiator comprising outer and intermediate sections arranged side by side lengthwise of the radiator, the outer sections 80 extending from end to end of the intermediate section and having top and bottom extensions which project toward each other above and below the intermediate section, said intermediate section being supported 85 by said outer sections, substantially as set forth.

4. A radiator comprising outer and intermediate sections arranged side by side lengthwise of the radiator and each having 90 upright radiating portions separated by intervening air spaces, said intermediate section being supported by and substantially 95 inclosed at its top, bottom and sides by said outer sections, substantially as set forth.

5. A radiator comprising outer and intermediate separate sections arranged side by side lengthwise of the radiator and each section consisting of a single hollow body having narrow upright radiating columns 100 which communicate with each other but are separated by intervening air spaces, the outer sections having base portions adapted to bear on a supporting surface and extending below the intermediate section, and the 105 intermediate section being secured to and entirely supported by the outer sections above the supporting surface, and means for independently controlling the supply of 110 heating fluid to said sections, substantially as set forth.

Witness my hand, this 20th day of November, 1908.

FRANCIS P. GALVIN.
